UNITED STATES PATENT OFFICE.

CHARLES H. WIDGER, OF LYNN, MASSACHUSETTS.

GAME-BOX.

SPECIFICATION forming part of Letters Patent No. 239,997, dated April 12, 1881.

Application filed June 16, 1880. (No model.)

To all whom it may concern:

Be it known that I, CHARLES HENRY WIDGER, of Lynn, in the county of Essex and State of Massachusetts, have invented certain new and useful Improvements in Game-Boxes, of which the following is a specification.

My invention consists in a certain novel construction and combination of parts, forming a simple, cheap, and effective device for keeping a record of the points in a game, or for marking the points made by several separate players; also, in a certain novel arrangement and adaptation whereby said invention may be applied to a card-case or cribbage-box.

Referring to the drawings forming part of this application, Figure 1 is a plan view of a card-case or cribbage-box opened upon its hinges, the pack of cards being shown therein in broken lines. Fig. 2 is a transverse section of said case or box, taken upon the line *xx* of Fig. 1, but showing the box closed. Fig. 3 is an enlarged section of one of the strips *F*.

It is well known to card-players that, with the exception of the ordinary cribbage-board, few, if any, of the card-boxes sold in the market contain devices for recording the various games which may be played with cards. It would be difficult to devise an apparatus which could be used to mark all possible games; but for the purposes of recording those which are most commonly used by card-players some device is greatly needed, and it is the purpose of my invention to supply this want.

In the drawings indicates a box or case suitable for containing a full pack of cards. This case may be made, if desired, of such proportions as to hold the cards laid in a single pile; but I prefer to increase the length and reduce the thickness of the case by forming it, as shown in the drawings, so that the pack may be stowed therein in two equal, or nearly equal, parts, as it may be much more conveniently carried in the pocket when made in these proportions. Within the bottom of the case or box *A*, I form the cribbage-board *B*.

A' is the lid of the box, and upon the inside of this lid I place a marking device or devices, which I construct in the following manner: Slots *C C C C* are cut longitudinally in the lid *A'*, extending from one end to about the cen-

ter of the cover, or as far as may be desirable. These slots are shallow, and are partly covered by strips of veneer, *D'*, cut from any ornamental wood, a narrow space, *D*, being left between the adjacent strips over the central part of the slots *C*. A block or strip, *F*, which may be covered with felt *a*, so as to closely fit within the inclosed slot *C*, is placed in said slot before the strips *D'* are fastened in place. A metallic button having a screw-shank is firmly attached to each of the blocks or strips *F* by screwing the threaded end into the wood composing the block. The shank of the button *G* projects between the veneer strips *D'*, so that the head or button itself rests upon the adjacent edges of said strips, between which it may be moved or slid longitudinally with ease, while at the same time the block upon which it is mounted fits closely enough in its slot to prevent any accidental movement or displacement. To each button is attached a pointer, *I*, projecting over the strip *D'*. A graduated scale is marked upon said strip, with suitable numeration indicated thereon, and the arrangement of the parts just described is such that the pointer *I* may be made to register with any one of the divisions marked on the scale by merely sliding the button along until it reaches the proper point.

A separate scale may be marked upon each strip *D'* or upon each edge of the three interior strips; or the central strip may have the same scale marked upon each edge, while separate and independent graduations are formed on the other strips. Moreover, by pivoting the head of the button *G* upon its shank, so that it may be revolved one-half a revolution, I may throw any one of the pointers *I* into engagement with either one of two different scales. The same result may also be accomplished by pivoting the pointer *I* upon the button *G*. So many different combinations are possible in this manner that a great variety of games may be marked with this device.

The remaining portion of the inside of the top is occupied by a slate or other surface capable of receiving legible marks from any pencil. I prefer to use for this purpose a strip of artificial slate, which may be simply fitted in place and renewed whenever desired. The convenience of combining such a tablet with the

other marking devices described, as well as with the cribbage-board, will be apparent to every player.

The blocks or strips F may be made square or slightly oblong; but I prefer to use a long strip and to mount the button at one end. The strip may be arranged to slide under the tablet L as the buttons are pushed toward the center of the cover. By using a long strip instead of a block, there is less danger of its binding in the slot, the button moves more steadily and smoothly, and the felt packing may be more easily attached.

When the pack of cards is stowed in the box 15 a vacant space will remain either at the end or between the two piles of cards, as the case is a little more than twice the length of an ordinary pack. By sliding the buttons G to the center of the cover they will, when the lid is 20 closed, fall into the space between the two halves of the pack, as shown in Fig. 2.

The marking devices, consisting of the buttons G and graduated strips D', may be used upon any game table or board as well as in 25 that described.

Having thus fully described my invention, what I claim as new, and desire to secure by Letters Patent of the United States, is—

1. A game-box, A, containing the cribbage 30 board B, the sliding markers G, and the recording-tablet L, the said box being composed of two parts hinged together, in order to provide for the cover A', all substantially as and for the purpose set forth.

2. In a game-board, the combination, with 35 differently-graduated scales, of the buttons G, mounted upon strips F, each button being adapted to slide in a straight line upon said scale and move independently of the others, substantially as set forth.

3. The two-part combination, with the game-board A A', of the graduated strips D', the sliding blocks F, provided with a packing of 40 felt, and the buttons G, having a suitable pointer, I, mounted on each one, substantially 45 as and for the purpose set forth.

4. The combination, with the buttons G, adapted to slide between the differently-graduated strips D', of the reversible pointer I, substantially as and for the purpose set forth. 50

5. As a new article of manufacture, a game-box, A, provided with hinged cover A' and having the cribbage-board B, the markers G G, adapted to slide between the graduated strips D', and provided with a reversible pointer, I, and the recording-tablet L, the buttons G being mounted upon felt-lined strips F, substantially as and for the purpose set forth. 55

In testimony whereof I have signed my name to this specification in the presence of 60 two subscribing witnesses.

CHARLES HENRY WIDGER.
